COMBINED PUMP AND MOTOR
CYLINDER COAXIAL

Raymond E. Minnix, Balboa, C. Z.

Application July 23, 1946, Serial No. 685,704

2 Claims. (Cl. 123—66)

1

This invention relates to improvements in internal combustion engines.

An object of the invention is to provide an internal combustion engine having a unique valved piston arrangement whereby the power of the engine is greatly increased during the operation thereof.

This invention is adapted for use with internal combustion engines of the radial, V type or in line type, and may also be used with engines employing the double acting, double piston construction, or may be used with various types of Diesel engines.

Another object of this invention is to provide a valved piston in opposed relation to the main piston, which is actuated by cam means on the crankshaft or cam shaft of an engine, such cam means having a spring pressed arm for engagement therewith, which through a linkage system connected to the valved piston, causes the operation thereof.

With the above and other objects and advantages in view, the invention consists of the novel details of construction, arrangement and combination of parts more fully hereinafter described, claimed and illustrated in the accompanying drawings in which:

Figure 1 is a vertical, sectional view of an engine embodying the invention;

Figure 2 is a front view of the cam wheel;

Figure 3 is a peripheral view thereof;

Figure 4 is a diagrammatic view of the engine in firing position;

Figure 5 is a diagrammatic view of the relative position of the cam wheel when the engine is in the position shown in Figure 4;

Figure 6 is a diagrammatic view of the engine in exhaust and intake position;

Figure 7 is a diagrammatic view of the relative position of the cam wheel when the engine is in the position shown in Figure 6;

Figure 8 is a diagrammatic view of the engine in transfer position;

Figure 9 is a diagrammatic view of the relative position of the cam wheel when the engine is in the position shown in Figure 8;

Figure 10 is a diagrammatic view of the relative position of the engine in compressed position and

Figure 11 is a diagrammatic view of the relative position of the cam wheel when the engine is in the position shown in Figure 10.

Referring more in detail to the drawings, the reference numeral 20 designates the motor block or cylinder which has secured thereto, in the conventional manner, the crank case 21. Jour-

2

nalled in bearing 22 in the sides of the crank case 21 is the crank 23 for the piston rod 24 of the piston 25 connected thereto by the wrist pin 26 and the block is provided with the intake connection 27 for connection to the intake manifold, and the exhaust connection 28 for connection to the exhaust manifold. The intake valve 29 is mounted in the block adjacent the intake 27, and the valve may be operated in any conventional manner. The elements of the engine previously described are somewhat conventional, and can be arranged to include radial V type or in line type of engine, as well as engines using the double action, double piston construction.

15 The invention contemplates extending the crank 23 to provide the portion 30 on which is keyed the wheel 31 having the cam 32 on one face of the rim thereof, and the cam has a 45 degree rise, and a 45 degree incline, making a 20 total cam surface of 90 degrees.

A bracket 33 secured to the block 20 and crank case 21 is provided with a bearing 34 for slidably mounting the rod 35 which is provided at one end with a fork 36 for journaling the pin axle 25 37 of the roller 38 which is mounted at right angles to the wheel 31, and is forced into engagement therewith by means of a coil spring 39, coiled about the rod 35, and interposed between the fork 36 and the bearing 34, and the reduced portion 30 of the bearing extends into the spring as shown in Figure 1. Pivotedly connected to the opposite end of the rod 35 by a pin 41 is a link 42 which is pivotedly connected to a rocker arm 43 by a pin 44, and the rocker arm is pivotedly mounted on 35 a pin 45 journalled in the extension arm 46 on the bracket 33.

At the upper end of the rocker arm 43 a pin 47 pivotally connects the arm to a link 48 which is pivotally connected by a pin 49 to the piston rod 50 of the piston 51, which is mounted in the block in opposed relation to the piston 25 and both pistons are provided with conventional rings 52.

The link 48 is fitted on the pins 47 and 49 respectively, so that the link is free to oscillate on either pin. This construction allows the rocker arm 43 to force the rod 50 downward through the link 48 without causing the rod to bend or causing excessive side thrust on the rod 50.

50 The piston 51 is provided with a spider 53 forming ports 54, and the spider is provided with a central threaded bore 55 for connection with the screw threaded end 56 of the rod 50.

The rod 50, at its threaded end, is provided 55 with a cavity 56 which is partially threaded to

receive the apertured, threaded insert 57, and the valve stem 58 of the valve 59 is mounted in the insert 57 and bore 60 in the rod 58. Coiled about the stem 58 is a coil spring 61 which is interposed between the insert 57 and a collar 62 formed on the stem, and the spring forces the valve closed at all times except during the transfer period, the operation of which will be later explained.

While the block is provided with a conventional intake valve, the exhaust of combusted gases is accomplished by means of an annular row of exhaust ports 63 which are formed in the block and communicating with the exhaust connection 28. The skirt of the piston 25 extends below these ports to keep them closed at all times except when the engine is in exhaust position.

The engine operates as a two cycle engine, and in Figure 4, the engine has fired, valve 29 is closed, piston 51 is at the top of the cylinder, and piston 25 is travelling downward. The roller 38 is just starting to engage incline of the cam 32. In Figure 6, the piston 25 is at exhaust position, ports 63 are open, the roller 38 is at the peak of the cam 32, the intake valve 29 is open, and the piston 51 is at its lowest point of decline. In Figure 8, the piston 25 is rising, the roller 38 has left the cam, and piston 51 is at its top position. This is called the transfer position, and the charge is forced through the open valve 59 into the cylinder when it is compressed as shown in Figure 10. In this position, the piston 25 is at top dead center, valves 29 and 59 are closed, the roller is on the wheel in opposite relation to the cam, and the charge is ready to be ignited to start the cycles as previously described.

The igniting means for either an internal combustion engine or a Diesel engine would be mounted in the cylinder in position to ignite the charge in the conventional manner.

Thus an engine has been provided that will fire on each stroke, will double its operative power, so that one cylinder will accomplish the work of several.

It is believed that the above description will fully explain the operation of the invention, and it is to be understood that minor changes in the details of construction, arrangement and combination of parts may be resorted to, providing

they fall within the spirit of the invention and the scope of the appended claims.

Having thus described the invention, what is claimed as new and desired to be secured by 5 Letters Patent is:

1. An internal combustion engine of the type described, comprising a cylinder block, a piston in said block, means for operating said piston, a second piston in said block in opposed relation to 10 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
2. An internal combustion engine of the type described, comprising a cylinder block, a piston in said block, means for operating said piston, a second piston in said block in opposed relation to 15 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
3. An internal combustion engine of the type described, comprising a cylinder block, a piston in said block, means for operating said piston, a second piston in said block in opposed relation to 20 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
4. An internal combustion engine of the type described, comprising a cylinder block, a piston in said block, means for operating said piston, a second piston in said block in opposed relation to 25 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
5. An internal combustion engine of the type described, comprising a cylinder block, a piston in said block, means for operating said piston, a second piston in said block in opposed relation to 30 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
6. An internal combustion engine of the type described, comprising a cylinder block, a piston in said block, means for operating said piston, a second piston in said block in opposed relation to 35 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
7. An internal combustion engine of the type described, comprising a cylinder block, a piston in said block, means for operating said piston, a second piston in said block in opposed relation to 40 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
8. An internal combustion engine of the type described, comprising a cylinder block, a piston in said block, means for operating said piston, a second piston in said block in opposed relation to 45 said first piston, a piston rod for said second piston, a valve in said second piston, means for operating said second piston, said means comprising a link connected to said rod, a rocker arm connected to said link, a second link connected to said rocker arm, and a spring pressed rod connected to said last mentioned link, and means for mounting said rod at right angles to said cylinder block, and means coacting with the means for operating said first piston connected to the means for operating said second piston.
